[57] CLAIM

We claim the ornamental design for a cabinet with monitor, as shown and described.

DESCRIPTION

FIG. 1 is a front side perspective view of a cabinet with monitor showing our new design;

FIG. 2 is a front view thereof;

FIG. 3 is a side view thereof;

FIG. 4 is a rear view thereof;

FIG. 5 is an opposite side view thereof;

FIG. 6 is a top plan view thereof;

FIG. 7 is another front side perspective view thereof with the door shown opened; and,

FIG. 8 is another front side perspective view thereof with the door shown opened and the monitor extended forward.
